EDGAR F. HATHAWAY, OF WELLESLEY, AND WALTER BIXBY, OF BOSTON, MASSACHUSETTS, ASSIGNORS TO SHAWMUTT ENGINEERING COMPANY, OF BOSTON, MASSACHUSETTS, A CORPORATION OF MASSACHUSETTS

YARN SPOOL

Application filed July 6, 1928. Serial No. 290,799.

This invention relates to yarn spools, and is especially adapted to yarn spools such as are used in axminster tube frames in which plural spools are placed end to end for the weaving of wide seamless rugs or carpets. The invention is particularly concerned for the most part with the improvement of tubular barrel yarn spools which are becoming increasingly popular in the trade and is intended to provide a construction and arrangement by which the substitution or replacement of new heads may be conveniently and securely made, while also making provision for the interchange of various types of gudgeon journals for rotatably supporting and also for interlocking the spools.

One important feature of the present invention resides in the combination with a removable end head with a fastening gudgeon interlocked with an interiorly disposed anchoring member to hold the removable end head firmly in position combined with means to prevent the accidental loosening of the fastening gudgeon that is sometimes occasioned by the continued revolution of the spool upon its supporting gudgeon. Another feature of the invention consists in the provision by which the head fastening gudgeon is provided with a disappearing axial pintle for rotatably and releasably supporting it in the end bearing bracket of the tube frame. These and other features of the invention will be described in detail in the following specification and will be defined in the claims hereto annexed.

In the drawings—

Fig. 1 is a side elevation in central section showing two end to end spools in interlocked relation.

Fig. 2 is a detail showing an endwise elevation of the head fastening gudgeon and its locking washer.

Fig. 3 is an end elevation of the inner end of the yarn spool showing its interlocking gudgeon.

Fig. 4 is a central cross sectional view of this gudgeon.

Fig. 5 is an end elevation of the opposite or adjacent spool.

Fig. 6 is a detail view in central cross

section showing the other interlocking gudgeon.

Fig. 7 is a plan view of the interlocking key used to prevent accidental rotation of the end head relative to the spool barrel.

Fig. 8 is a cross sectional view of the anchoring member and the interlocking key.

Fig. 9 is an end elevation of the parts shown in Fig. 8.

According to the practice illustrated in the drawings, we provide a tubular spool barrel 1 in whose opposite ends are inserted a flanged transverse anchoring member 2 provided with an internal bored and threaded hub 2^a, and having at one side a radial slot 65 2^b for the reception of a locking key herein-after to be described.

The end heads 3 of the spool are of disk-like construction and are provided with an annular offset shoulder as at 3^a adapted to fit in to the open end of the tubular barrel, so as to be co-axially aligned therewith, said heads being fastened in position by means of fastening gudgeons 4.

These fastening gudgeons 4 have their outer ends somewhat larger than the inner shank portion to form a circumferential shoulder 4^a, which engage the edge of the central perforation formed in the head 3 and which act to clamp the head firmly against the end of the tubular barrel by means of the interlocking or screw threaded engagement between the inner end of the shank and the interior threaded hub portion of the anchoring member 2.

The outer enlarged end of the gudgeon is of polygonal form and, between the shoulder and the edge portion of the head surrounding the central aperture is interposed a washer 9 of general circular form having its periphery notched, as shown at 9^a, and having opposite said notch a flexible tongue 9^b for a purpose hereinafter described.

The gudgeon is counter-bored from its outer end and the inner end wall is perforated by a smaller bore to leave an annular seat for a compression spring 6, which engages the shoulder of an elongated pintle 5 to force the pintle normally outward while allowing it to be pressed entirely inside the

bore when inserting the spool in the bearing arms of the tube frame brackets. To prevent the spring from ejecting the pintle too far, the inner protruding end of the pintle, as shown at 5^a, is upset to form projections limiting the outward movement of the pintle. It will thus be seen that the gudgeon with its disappearing pintle forms a self-contained unit that can be readily removed from and restored to operative position when it is desired to replace the end head of the spool.

In assembling the device the self-contained gudgeon unit is inserted first through the locking washer 9 and then through the central aperture in the end head until its inner threaded end engages the internal thread of the anchoring member 2. A wrench applied to the polygonal head of the gudgeon permits it to be screwed tightly to clamping position to fasten the end head concentrically in place. When this is done the outer end of the tongue 9 is doubled upon or folded upon itself in position so that its squared end will engage the flat peripheral face of the polygonal head.

Before the parts are assembled, however, a key 7, in the shape of a sheet metal cross, is inserted through the aperture or slot 2^b in the anchoring member and the slot 3^b in the head is turned to register with the outer end of this key 7 when the end head is placed in position against the end of the barrel. The cross arms are of a width corresponding to the space between the flat face of the anchoring member 2 and the opposed face of the offset hub portion of the head 3, so that the key cannot rock and consequently acts to prevent accidental rotation of the head, since the anchoring member 2 is permanently fastened either by spot welding or equivalent means inside of the tubular barrel.

It will, therefore, be seen that the heads are very easily replaceable and, when replaced are as securely fastened as when the spools are originally made. Furthermore, the loosening of the clamping engagement of the gudgeon with the anchoring member is positively prevented because not only does the key 7 lock the end head against accidental rotation, but the locking washer 9 acts as a positive preventative against the accidental rotation of the gudgeon itself, since its notch 9^a interlocks with the outwardly projecting end of the key, which latter is interlocked with the stationary or fixed anchoring member. The provision for locking the gudgeon against accidental rotation is important, because without such means the gudgeons frequently show a tendency to work loose, thus allowing the head to become loose and causing trouble.

In multiple spool tube frames it is often desired to make provision for interlocking two adjacent spools together to prevent un-

equal rotation thereof. Moreover, the middle bearing stands are often made with a larger bearing aperture to support the spools than are the end brackets. In this case two annular coupling members, a female member 11 and a male member 12, are secured to the adjacent ends of the aligned spools by means of fastening gudgeons 10 having threaded engagement with inserted anchoring members 2 similar to those already described. A key 7 inserted between the end head 3 and the anchoring member 2, so as to pass through two registering slots in the respective members and engage a notch 11^a in the periphery of the gudgeon 11, serves to prevent accidental rotation of the bearing members and of the head.

When winding the yarn on the spools it is the practice to rotate the spool to draw off the yarn from the yarn package and, in order to make proper provision for this the key-receiving slots 3^b in the head are extended outward far enough to make provision for the reception of an eccentric pin in the revolving clutch member that rotates the spool in order to wind on the yarn. As the clutch member forms no part of the present invention it is illustrated only in dotted lines to the right of Fig. 1 in order to show how such a clutch pin may penetrate this slot or opening 3^b in order to impart rotative movement to the spool.

What I claim is:—

1. In a yarn spool the combination with a tubular barrel having an interiorly disposed anchoring member provided with an eccentric slot, an end head provided with a slot adapted to register with the slot in the anchoring member, a key projecting through the two registering slots, an axially disposed fastening member for releasably securing the end head to the anchoring member, and a locking member having interlocking rotation-preventing engagement with the gudgeon and having also interlocking engagement with said key to prevent accidental rotation and loosening of the fastening gudgeon.

2. In a tubular barrel yarn spool a fastening gudgeon for fastening the end head of the spool to the barrel, embracing in its construction an elongated gudgeon having a polygonal outer end, and having a reduced cylindrical inner end provided with a screw thread for engagement with the barrel structure, said gudgeon having a longitudinal interior bore, a spring pressed pintle mounted in said bore to project through both ends of the gudgeon, and means for preventing the expulsion of the pintle by the spring.

3. A self-contained bearing gudgeon for fastening the end head of a yarn spool to the barrel portion and rotatably supporting the spool, embracing in its construction a hollow gudgeon having a polygonal outer end, and a cylindrical externally threaded inner end,

a bearing pintle loosely mounted in said hollow gudgeon and having an enlarged outer end and a reduced inner end projecting beyond the respective ends of the gudgeon, a 5 spring tending normally to force said pintle outward, and means carried by the inner projecting end of the pintle to limit the outward movement of the pintle.

4. In a yarn spool the combination with a 10 tubular barrel having an interior anchoring member provided with an eccentrically disposed slot, an end head provided with a similar slot adapted to be placed in registry with the first-named slot when the end head is 15 held in normal position, a connecting key projecting through both slots, a fastening gudgeon for releasably securing the end head to the anchoring member, locking means engaging both the key and the gudgeon whereby 20 the gudgeon and the end head are positively held against accidental rotation and loosening.

5. In a yarn spool the combination with a tubular barrel having an interiorly disposed 25 anchoring member integrally secured thereto, of a detachable end head having an annular shoulder fitting into the end of the barrel, an axially disposed fastening gudgeon penetrating the center of the end head and having 30 threaded engagement with the anchoring member to secure the end head tightly to the barrel, means interposed between and interlocking engaging the end head and the anchoring member to prevent rotative displacement 35 of the end head, and means for releasably interlocking the gudgeon with the end head to prevent loosening of the threaded connection between the gudgeon and the anchoring member.

40 6. In a yarn spool the combination with a tubular barrel having an interiorly disposed anchoring member, a centrally perforated end head provided with an annular shoulder forming guiding engagement with the end 45 of the barrel, a fastening gudgeon penetrating the central aperture of the end head and having threaded engagement with the anchoring member to firmly clamp the end head against the barrel, a removable key interposed between the anchoring member and the 50 end head and penetrating aligned apertures in both said members to prevent rotative displacement of the end head, and means for interlocking the outer portion of the gudgeon 55 with the projecting end of said key to prevent rotative loosening of the gudgeon.

In witness whereof, we have subscribed the above specification.

EDGAR F. HATHAWAY.
